CLIFFORD W. WATERMAN, OF PITTSBURG, KANSAS, ASSIGNOR TO THE PITTSBURG BOILER AND MACHINE COMPANY, OF PITTSBURG, KANSAS

COMBINED PICKING TABLE AND REFUSE CONVEYER

Application filed May 31, 1930. Serial No. 458,173.

My invention relates to improvements in coal-handling machinery, more particularly in a combined picking table and refuse conveyor, and it consists in the combinations, 5 constructions, and arrangements herein described and claimed.

An object of my invention is to provide a device for facilitating the removal of refuse from coal so as to leave the latter in a clean 10 and salable condition.

A further object is to provide means whereby the refuse may be removed and immediately conveyed to any suitable location, such as a dumping ground, without requiring any 15 additional effort on the part of the worker.

A further object is to provide a combined picking and refuse conveyor of the endless type in which means is provided for preventing the clogging of the conveyor. This means 20 consists in a novel arrangement of overlapping plates which are so curved as to easily pass around sprockets at the ends of the device, the plates forming a continuous bearing surface at all times as distinguished from 25 other conveyors in which the plates are opened up or separated as they pass around the sprockets.

A further object is to provide a device of the type described in which the lower or return portion is utilized for conveying the refuse, and in which the refuse is automatically delivered to chutes, thus obviating any further labor on the part of the worker than the usual depositing of the refuse, which of course 35 is necessary in all devices of the type.

Other objects and advantages will appear in the following specification, and the novel features of the invention will be particularly pointed out in the appended claims.

My invention is illustrated in the accompanying drawings, forming part of this application, in which

Figure 1 is a side elevation of the device, 45 the supporting floor being shown in section,

Figure 2 is a plan view,

Figure 3 is an enlarged section along the line 3-3 of Figure 1,

Figure 4 is an enlarged section along the 50 line 4-4 of Figure 3, and

Figure 5 is an enlarged section along the line 5-5 of Figure 2.

In carrying out my invention I provide a frame consisting of uprights 1 which are preferably angle irons and to which are fastened cross beams 2, as shown in Figure 3. Secured to the upper inner sides of the members 1 are angle irons 3, while similar angle irons 4 are secured to the members 1 near the bottoms thereof. In Figure 3 I have shown an upright 55 with the upper and lower angle irons on one side of the device, but it will be understood that the opposite side is provided with similar uprights and angle irons.

On each side of the device, and spaced inwardly from the uprights 1, are supporting bars 5, see Figure 3, which are secured to the cross members 2. To these bars 5 are secured plates 24 which extend upwardly beyond the cross beams 2. Angle irons 6 are secured to the upper ends of the plates 24 and rest on the cross beams 2. Similar angle irons 7 are secured to the lower ends of the plates 24, and these angle irons form runways as will be described later. 65

The bearing surface of the conveyor consists of a series of plates 8 of the shape best shown in Figure 4. These plates are of a general rectangular shape and are elongated as shown in Figure 2, the long dimension of 70 the plates extending transversely of the longitudinal dimension of the conveyor as a whole. One edge of the plate is curved as shown at 8a in Figure 4, and at the opposite edge is welded or otherwise secured a curved portion 8b. The portions 8a and 8b are curved concentrically about the central axial line of rollers 9. At the ends of the plates, that is to say at the sides of the conveyor, 75 the plates have strips 8c for preventing the material carried thereby from falling off. 80

The rollers 9 are secured to the body portion of the plates by means of angular shaped brackets 10, and the axles of adjacent pairs of rollers are connected by means of links 11 and 11a. As will be seen from the drawings, these links are arranged in pairs, the links 11 being on the outside of the links 11a. 85

At one end of the device is the driving mechanism. This consists, in the present in- 90

stance, of a power shaft 12 connected to any suitable source of power, not shown, and a set of reducing gears including the gears 13, 14, the gear 15 on the opposite side, 16, 17, and 18. On the shaft 19 of the gear 18 is a pair of sprocket wheels 20 which are disposed on each side of the central longitudinal axis of the machine. Similar sprockets 21 are carried by the shaft 22 at the opposite end of the conveyer. The teeth of the sprockets 20 and 21 are arranged to project between the links 11a, and the rollers 9 are received in the recesses between the teeth so as to afford a positive driving means.

Disposed along each side of the conveyer are chutes 23. These chutes have an inclined bottom portion 23a, see Figure 3; which permits material deposited therein to pass down onto the return portion of the conveyer plates 8. The plates 24 form a means for preventing the refuse from interfering with the operation of the conveyer. Deflecting plates 25 are secured in position to deflect the refuse into chutes such as that shown at 26 in Figures 1 and 2. These chutes may lead to any suitable source of deposit such as other conveyers, not shown.

From the foregoing description of the various parts of the device, the operation thereof may be readily understood. The workers, who clean the coal of refuse, stand on each side of the conveyer between the chutes 23. The movement of the endless conveyer is that shown by the arrows in Figure 2. Coal may be deposited upon the conveyer table, made up of the plates 8, at the left-hand end in Figure 2 by any suitable means, not shown, and as it passes along, the refuse is picked out and deposited in the chutes 23. Here it falls down to the lower part or the return portion of the endless conveyer and is carried in the opposite direction on the outer side of the plates 24. It will be observed that the angle irons 6 and 7 form a support for the belt conveyer, but the plates 8 are also supported by the angle irons 4 so that in certain constructions the angle irons 7 may be dispensed with and the support for the return portion of the belt be merely that at the outer ends upon the angle irons 4.

One difficulty with an endless belt has been to provide plates which would support the load and yet it would pass around sprockets without being clogged up due to the opening up of the space between the plates. In the present instance, it will be observed that there is a continuous bearing surface even when the plates are passing around the sprockets. This is due to the construction shown in Figure 4, there being a relative movement between the parts 8b and 8a around the axes of the rollers as a center. The portion 8a however is always in contact with 8b so there is no chance for particles of coal or refuse to get between the plates and

thus interfere with the proper working of the mechanism.

Use of this device obviates the necessity of long inclined chutes for the refuse, since the lower part of the endless belt is made use of for conveying the refuse to a point where it is desired to dump it.

I claim:

1. In an endless conveyer coal handling machine of the class described, the combination of a frame, an endless belt, means for causing the travel of the upper portion of the belt in one direction and the lower portion of the belt in another direction, a plurality of upper refuse receiving chutes disposed on one side of the conveyer belt and arranged to deliver the refuse material on the inner surface of the lower portion of the belt on the same side thereof, a lower refuse material receiving chute, and a stationary deflecting plate positioned immediately above said inner surface and arranged for deflecting the refuse material off the edge of the belt on said side thereof directly above said lower chute, said frame carrying upper and lower runways for the belt disposed between the upper and lower portions of the belt, the belt comprising a series of plates, the plates carrying rollers for traveling on said runways, said upper and said lower runways being substantially centrally disposed intermediate of the end portions of said plates and being provided with a vertical plate disposed intermediate of the upper and lower portions of the belt and being adapted to shield the lower runway from the refuse deposited on the inner surface of the lower portion of the belt.

2. In an endless conveyer coal handling machine of the class described, the combination of a frame, an endless belt, means for causing the travel of the upper portion of the belt in one direction and the lower portion of the belt in another direction, a plurality of upper refuse receiving chutes disposed on one side of the conveyer belt and arranged to deliver the refuse material on the inner surface of the lower portion of the belt on the same side thereof, a lower refuse material receiving chute, and a stationary deflecting plate positioned immediately above said inner surface and arranged for deflecting the refuse material off the edge of the belt on said side thereof directly above said lower chute, said frame carrying upper and lower runways for the belt disposed between the upper and lower portions of the belt, the belt comprising a series of plates, the plates carrying rollers for traveling on said runways, said upper and said lower runways being substantially centrally disposed intermediate of the end portions of said plates and being provided with a vertical plate disposed intermediate of the upper and lower portions of the belt and being adapted to

shield the lower runway from the refuse deposited on the inner surface of the lower portion of the belt, each of said conveyer plates being curved at one end and being straight at their other end, said straight end having fixedly secured to its top side a curved end plate, said curved end plate being adapted to provide a support and a bearing for the curved end of another of said conveyer plates.

3. In an endless conveyer coal handling machine of the class described, the combination of a frame, an endless belt, means for causing the travel of the upper portion of the belt in one direction and the lower portion of the belt in another direction, a plurality of upper refuse receiving chutes disposed on one side of the conveyer belt and arranged to deliver the refuse material on the inner surface of the lower portion of the belt on the same side thereof, a lower refuse material receiving chute, and a stationary deflecting plate positioned immediately above said inner surface and arranged for deflecting the refuse material off the edge of the belt on said side thereof directly above said lower chute, said frame carrying upper and lower runways for the belt disposed between the upper and lower portions of the belt, the belt comprising a series of plates, the plates carrying rollers for traveling on said runways, said upper and said lower runways being substantially centrally disposed intermediate of the end portions of said plates and being provided with a vertical plate disposed intermediate of the upper and lower portions of the belt and being adapted to shield the lower runway from the refuse deposited on the inner surface of the lower portion of the belt, each of said conveyer plates being curved at one end and being straight at their other end, said straight end having fixedly secured to its top side a curved end plate, said curved end plate being adapted to provide a support and a bearing for the curved end of another of said conveyer plates, said conveyer plates being rectangular and elongated, the long dimension of the plates extending transversely of the longitudinal dimension of the conveyer as a whole.

Signed at Pittsburg, in the county of Crawford and State of Kansas this 26th day of May, A. D. 1930.

CLIFFORD W. WATERMAN.
